UNITED STATES PATENT OFFICE.

EMIL NOVITZKY, OF DETROIT, MICHIGAN.

CENTERING GAUGE FOR LATHES.

1,414,483.

Specification of Letters Patent. Patented May 2, 1922.

Application filed April 16, 1921. Serial No. 461,939.

To all whom it may concern:

Be it known that I, EMIL NOVITZKY, citizen of Hungary, residing at Detroit, in the county of Wayne and State of Michigan, have invented certain new and useful Improvements in Centering Gauges for Lathes, of which the following is a specification.

This invention relates to a centering gauge for lathes, being more particularly for use 10 in connection with work which is secured in place by clamping upon a face plate.

The invention has for an object to provide a simple and inexpensive device of this kind characterized by easy application and use.

15 For further comprehension of the invention, and of the objects and advantages thereof, reference will be had to the following description and accompanying drawings, and to the appended claims in which the various novel features of the invention are 20 more particularly set forth.

Fig. 1 of the drawings is a side view of a centering gauge constructed according to the invention.

25 Fig. 2 is a longitudinal sectional view thereof.

Fig. 3 is a transverse section on the line 3—3 of Fig. 2.

Fig. 4 is an enlarged fragmentary longitudinal section showing the means for securing the movable pin against inward movement.

Fig. 5 is a transverse section on the line 5—5 of Fig. 4.

35 As here shown my improved centering gauge comprises a cylindrical casing consisting of an outer element 10 having one end closed as at 11 and the opposite end open and interiorly screw-threaded, one end 40 of a sleeve 12 being screwed into the outer element 10. The closed end 11 is formed with a suitable socket 11' to receive the usual center piece 13 of the lathe.

45 Slidable in the sleeve 12 is a pin 15 having its outer end 15^a pointed as at 15^b to engage the work. Located in the chamber 16 formed within the casing 10 is a coiled expansion spring 17 which bears against the end of the pin 15 and normally presses the 50 same forward, the pin 15 having an enlarged head 15' which is accommodated in the enlarged rear end 18 of the bore of the sleeve and is adapted to engage an interior shoulder in the sleeve 12 to limit the for-

ward movement of the pin under the influence of the spring 17. 55

Upon the projecting forward end of the pin 15 is slidably carried a collar 20 exteriorly screw threaded for about one-half its length and having the other half tapering 60 toward its end as at 20' and longitudinally slotted at four points as at 21, this slotted end being toward the sleeve 12. Upon the collar 20 is threaded a nut 24 having at one end an inwardly projecting flange 25 whose 65 annular wall is tapered in correspondence to the split collar element 20' and is adapted to engage the latter.

In the drawings I have indicated at 27 the work to be centered, the same being shown 70 as clamped upon a face plate 28 in the usual manner. As an instance of the manner of use of my improved gauge it is assumed that the work is to be drilled at a point marked in the usual manner by a center punch. 75 The work is clamped to the face plate 28 with this point approximately centered. The gauge is placed in position with the lathe piece 13 engaging in the socket 11' and the pointed end 15^b of pin 15 engaging in 80 the center punch marking in the work, the spring 17 pushing the pin against the work. The collar 20 is then moved until its split end bears on the end of sleeve 12, and the nut 24 is then tightened causing the flange 85 25 to contract the split portion of the collar and the latter to grip the pin. With the parts in this position the pin cannot move inwardly to displace it from the center mark while at the same time it is still under the 90 forward pressure of the spring 17.

The gauge element 30 of well known type is then mounted on a fixed support in position with its feeler 31 in contact with the outer end 15^a of pin 15 and the lathe shaft is 95 rotated. As will be apparent, if the work is not properly centered, there will be a vibratory movement of the pin 15 during this rotation which will be indicated on the gauge 30 and the work can then be shifted until 100 the gauge 30 shows that it is properly centered.

Having thus described my invention what I claim as new and desire to protect by Letters Patent is as follows:—

105 1. A centering gauge for lathes comprising a casing, a pin slidable in said casing and having a pointed end projecting therefrom,

and a spring in said casing bearing against the inner end of said pin, and a collar adjustable along said pin adapted to permit free outward movement thereof but to limit the 5 inward movement thereof and means for clamping said collar upon said pin.

2. A centering gauge for lathes comprising a casing, a pin slidable in said casing and having a pointed end projecting therefrom, and a spring in said casing bearing against the inner end of said pin, and a collar adjustable along said pin adapted to permit free outward movement thereof but to limit the inward movement thereof, said 10 15 collar comprising an exteriorly screw threaded portion and a tapered unthreaded split

portion, and a nut screwed on said collar and having a part adapted to freely engage said tapered portion.

3. A centering gauge for lathes comprising a pair of telescopic elements, a spring urging said elements to expanded position, and means adapted to permit free expansion movement of said elements under the influence of said spring but to limit contractive 20 movement thereof, said means comprising a split collar adjustable on said pin, and a clamp element adapted to engage said collar. 25

In testimony whereof I have affixed my signature.

EMIL NOVITZKY.
